UNITED STATES PATENT OFFICE.

JOSEPH HENRY SAMS, OF WEST KENSINGTON, COUNTY OF MIDDLESEX,
ENGLAND.

FIRE-PLACE FRONT.

SPECIFICATION forming part of Letters Patent No. 349,813, dated September 28, 1886.

Application filed July 1, 1885. Serial No. 170,431. (No model.) Patented in England September 19, 1884, No. 12,619.

To all whom it may concern:

Be it known that I, JOSEPH HENRY SAMS, a citizen of Great Britain, and a resident of West Kensington, in the county of Middlesex, 5 England, have invented certain new and useful Improvements in Fire-Place Fronts, of which the following is a specification.

The object of my invention is to so construct and arrange a chimney or mantel piece that 10 the entire opening therein for the grate or fire-place may be exposed to any desired extent when the latter is in use and completely closed when not in use so that when in the latter position it is completely concealed and 15 the mantel front rendered as ornamental as may be desired.

To this end the invention consists in the combination, with the mantel or chimney piece, of doors or screens secured thereto and adapted 20 to be swung toward or from each other, so as to completely or partially close in or expose the grate or fire-place, and in the other features, more particularly hereinafter set forth and claimed, reference being had to the drawings 25 accompanying and forming part of this specification, wherein like letters indicate like parts.

In these drawings, Figure 1 is a front plan view of a mantel or chimney piece embodying 30 my invention. Fig. 2 is a horizontal section on the line $x-x$, Fig. 1; Fig. 3, a front plan view, and Fig. 4 a like view of a modification of Fig. 1.

In Figs. 1, 2, 3, and 4 the means for closing 35 the opening in the chimney or mantel are screens or frames pivoted or hinged to or at the jambs of the chimney or mantel piece.

A A represent the swinging frames or screens, which may be made of metal, wood, or any 40 other suitable material. While they may be hinged directly to the jambs, I prefer, as affording a more ornamental and secure attachment thereto, that they be attached to columns or pillars B, which are formed or provided 45 with dowels or pintles B' B' at their ends, which enter sockets or holes formed at suitable points in the upper and lower parts of the casing, or in metallic or other step pieces or supports attached thereto. When these columns 50 are used as the pivotal supports of the

swinging screens, the front faces of the jambs may be hollowed out or concaved, as shown in Figs. 1 and 2, to receive the columns for, say, about half their diameter, and the column and the jambs may be given such ornamental contour and finish as is desired. 55

The swinging frames or screens A A may be solid and of one material, or the frames A A may be filled in with panels of different material. For instance, the panels may be of plain, decorated, or colored glass, or of papier-maché, each main frame A forming, with its filling, a complete swinging screen. In order, however, to increase the capability of use of the screen, both for closing the fire-place opening when the same is not in use and for use as a fire-screen when the fire-place is in use, I prefer to pivotally mount the panels within the main frames A A. To this end, therefore, supplemental frames D D, Figs. 1 and 2, are 60 secured within the main frames A A by pivots D' D' in vertical line, and these supplemental frames are filled with suitable panels, E E, which may be plain or ornamented glass, mirrors, &c. As these supplemental frames 65 D D can be turned entirely around, the contained panels E E may be finished differently on their opposite faces, so that the screen may be made to present a different appearance whenever desired, thus changing the decorative effect of the mantel or chimney piece. 70 As shown, these supplemental frames may be turned to assume any angle with the main frames, so that when the fire-place is thrown open and in use they may be used as fire- 75 screens to intercept the heat radiated in any direction.

Instead of pivoting the supplemental frames D D within the main frames A A on a vertical line, they may be pivoted therein on a horizontal line, as shown in Figs. 3 and 4, so that they can be tilted at any angle desired. In this plan the decorations of the panels can be more fully and conveniently seen and inspected, while if the panels be provided with 80 mirrors they can be placed in such position as best enables them to serve as regulating-surfaces for the contents of the room or for the persons desiring to so use them. It will be 85 seen thus that the screens can be placed in 90 95 100

any desired radial position intermediate between complete closure and complete opening of the fire-place; that they may be used as screens for protecting any desired part of the 5 room from the fire; that when used as screens, if either of the panels be clear or ground glass the fire may be seen without excessive heat, while if properly-colored glass be used the fire, by reason of the colors in such glass, may 10 be made to add greatly to the decorative effect of the room; and that if the mirrors be used they serve also as dwarf cheval looking-glasses.

In Fig. 7 the screen for one-half the opening is made of two parts, A A, hinged together, so as to be folded back upon each 15 other. Back of the jamb two pockets or recesses are provided, in which they may be slid.

I am aware that doors have been hinged to the upper part of the sides of grate-frames or 20 fire-places and adapted to be swung forward and close the upper part of the fire-place, so as to act as a blower therefor, increasing the draft and aiding in quick combustion. Such I do not claim, as such construction in no wise 25 embodies my invention, which does not relate to any change or improvement in grates or fire-places or in the construction of blowers therefor, but relates, as before stated, entirely to improvements in mantel or chimney pieces.

30 Having thus fully described my invention, what I claim, and desire to secure by Letters Patent, is as follows:

1. The combination, with a mantel or chimney piece, of doors or screens pivotally secured or hinged thereto extending from top 35 to bottom of the fire-place opening and adapted to be swung in any desired radial position intermediate between complete closure and com-

plete opening of the fire-place, substantially as and for the purposes hereinbefore set forth. 40

2. The combination of a mantel or chimney piece, main screen-frames pivotally secured or hinged thereto and extending from top to bottom of, so as to cover at will, the entire fire-place opening, and supplemental frames pivotally mounted in said main screen-frames, substantially as set forth. 45

3. The combination of a mantel or chimney piece, screen-frames extending from top to bottom, so as to inclose at will the entire fire-place opening, pillars or columns, one for and attached to each screen-frame and doweled at its ends to form the pivotal connection of the screen-frames to the mantel or chimney piece, substantially as set forth. 50

4. The combination of a mantel or chimney piece, main screen-frames provided with supplemental frames, substantially as described, and extending from top to bottom of the fire-place opening to completely inclose the same, 60 when desired, pillars or columns, one for and attached to each main screen-frame and doweled at its ends to form the pivotal connection of the main screen-frames to the mantel or chimney piece, substantially as set forth. 65

Signed at London, in the county of Middlesex, England, this twelfth day of June, A. D. 1885.

JOSEPH HENRY SAMS.
